CLAIM

The ornamental design for a wine bottle ring, as shown and described.

DESCRIPTION

FIG. 1 is a perspective view showing my wine bottle ring design mounted on a wine bottle;

FIG. 2 is a fragmentary enlarged view of the ring shown in FIG. 1;

FIG. 3 is a perspective view of a wine bottle ring per se showing my new design;

FIG. 4 is a top plan view thereof, it being understood that the bottom plan view is a mirror image thereof;

FIG. 5 is a front view thereof;

FIG. 6 is a rear view thereof;

FIG. 7 is a side view thereof, it being understood that the opposite side is a mirror image thereof; and,

FIG. 8 is a perspective view showing my wine bottle ring with one of the charms removed and mounted on the stem of a wine glass.

The portions shown in broken lines in FIGS. 1, 2 and 8 are for information only and form no part of the instant design.
